UNITED STATES PATENT OFFICE.

ROBERT H. TAYLOR, OF TONGANOXIE, KANSAS.

CORN-HARVESTER.

SPECIFICATION forming part of Letters Patent No. 280,687, dated July 3, 1883.

Application filed November 23, 1882. (No model.)

To all whom it may concern:

Be it known that I, ROBERT H. TAYLOR, a citizen of the United States, and a resident of Tonganoxie, in the county of Leavenworth and State of Kansas, have invented certain new and useful Improvements in Corn-Harvesters; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a top or plan view of my stalk-cutter. Fig. 2 is a side view. Fig. 3 is also a side view. Fig. 4 is a rear view, and Fig. 5 is a plan view of the gearing detached from the machine.

20 This invention has relation to machines for cutting standing corn or cornstalks; and it consists in the construction and novel arrangement of devices, as hereinafter set forth, and particularly pointed out in the appended claims.

25 In the accompanying drawings, the letter A designates the longitudinal beams of the frame; B, the cross-bars, and C a horizontal oblique beam on the side of the frame next to the corn. The frame is divided by the central longitudinal beam and the middle cross-bar into four parts, whereof the parts D and E, diagonally opposite each other, are respectively floored to receive the driver and to afford a standing-place for the shocker. The other two parts, F and G, also diagonally opposite each other, are designed, respectively, for the mechanism of the cutting device and for the trap-compartment in which the shock is built, and from which it is discharged in standing form.

30 On the right of the frame, upon the oblique beam C, is constructed an oblique side frame, H, the front end of which extends forward of the cutter, and forms a guide and gatherer for the stalks to be cut.

35 K indicates the main supporting and drive wheel, which is rigidly attached to the shaft a, near the middle of the front portion of the frame, so that this wheel is never in the standing corn.

40 Near the rear end of the machine, on each

side, is arranged a caster-wheel, L, that on the right being guarded by the oblique frame H, so that its movements are unobstructed by the standing corn.

45 The shaft a extends from the middle drive-wheel, K, to the right, and carries a cog-wheel, b, which engages a pinion, c, on a small horizontal shaft, d, which carries at its outer end the bevel-pinions e and g, arranged back to back, as shown in the drawings.

The stem f of the cutter N is provided with a bevel-wheel, h, which engages the pinion e, and the pinion g engages a bevel-wheel, k, at the lower end of the reel-stem l, which extends 55 upward, and is provided with a radially-armed wheel or reel, M, whereby the tops of the stalks are pushed toward the rear as the stalks are cut off by the knife N. The knife is rotary, having cutting-arms m, which operate in 60 succession upon the stalks. Below the front portion of the knife a V-shaped plate is secured to the frame, forming an abutment against which the knife works. The machinery for operating the cutter and reel is designed to be 65 housed in to keep it free from obstructions and dust.

To the upper portion of the frame H is attached a guide-bar, P, which is curved inward at its rear end, as indicated at p, and serves to 70 guide the falling stalks toward the opening n at the inner front corner of the trap-compartment G. An oblique guide-bar, P', extends from the standard R, which supports the upper end of the reel-stem, to the front post of 75 said corner opening, n, and also serves to guide the falling stalks to said opening. The trap-compartment G is arranged diagonally to the left and rear of the frame. It is bounded on the outside and front by a guard-wall, s, and 80 on the inside by a guard-wall, s', the front end of which is separated from the guard-wall s by the corner opening, n, through which the stalks fall. In rear the compartment is provided with a gate, R, which is pivoted to the rear end 85 of the inside wall, s'. The bottom of the compartment is formed by the trap-doors S, which are placed side by side, being hinged to the frame at their outer edges and meeting along the middle of the compartment, as shown in 90 the drawings. These trap-doors are provided in rear with projections t, which, when the

doors are closed, engage a cross-bar, *v*, secured to the lower portion of the gate *R* when the latter is closed. When the gate is opened, the trap-doors are released and fall, letting out 5 the shock which has previously been formed and bound by the shocker, standing on the floor at *E*.

In order to hold the gate closed, angle-catches *z z* are pivoted to the rear end of the 10 outside wall, *s*, their ends being provided with slots, and a pin connecting them with an operating-rod, *T*, which extends forward within reach of the driver. The catches *z z* are arranged one above the other, and when the 15 gate *R* is closed engage extensions *w* of the upper and lower cross-bars, *W*, of said gate.

In order to discharge the shock after it has been formed, it is only necessary to pull the rod *T*, which releases the gate, allowing it to 20 be pushed open by the expansive force of the shock, or by the shocker releasing the trap-doors, which fall promptly, so that the shock descends in standing form. A jointed device for compressing the shock for binding may be 25 connected to the wall of the shock-compartment.

A latch may be connected to the bottom frame to engage the trap-doors, and will serve to hold up the front ends of the latter while the 30 shock is being formed. The operating-rod should be connected with this latch, so as to unfasten it when it is pulled to unlatch the gate.

A trap-bottom upon which the shock is formed, adapted to open downward in two sections and deposit the shock in a standing position on the ground, has been employed in corn-harvesters prior to my invention. Revolving cutters and a reel for pressing the stalks down to be cut are also old, and broad 40 claims are made to neither of these constructions.

Having described this invention, what I claim, and desire to secure by Letters Patent, is—

1. In a corn-harvester, the combination, with 45 the bottom trap-doors, *S S*, having rear projections, *t*, of the hinged rear gate, *R*, having a cross-bar at its lower portion to engage said projections and hold the trap-doors up when the gate is closed, substantially as specified.

2. A corn-harvester having the shock-compartment *G*, diagonally opposite the cutter, and provided with the corner opening, *n*, the guides *P* and *P'*, leading from the cutter there- 50 to, the hinged bottom doors having projections *t*, the hinged rear gate, *R*, engaging said projections, the angle-catches *z*, pivoted together, and the operating-rod *T*, substantially as specified.

In testimony whereof I affix my signature in presence of two witnesses.

ROBERT H. TAYLOR.
